UNITED STATES PATENT OFFICE.

BENNO VOM EIGEN, OF NEWARK, NEW JERSEY, ASSIGNOR TO AUGUST GOERTZ & CO., A CORPORATION OF NEW JERSEY.

MATCH BOX OR CASE.

1,283,376.

Specification of Letters Patent. Patented Oct. 29, 1918.

Application filed February 27, 1917. Serial No. 151,161.

To all whom it may concern:

Be it known that I, BENNO VOM EIGEN, a citizen of the United States, residing at Newark, in the county of Essex and State of New Jersey, have invented certain new and useful Improvements in Match Boxes or Cases; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in match-boxes, such as are carried in the pocket, or cases; and, the present invention relates, more particularly, to a novel construction of pocket match-box, and a novel means employed in connection therewith for readily placing in position upon the inner surface of the lid or cover of the match-box, and for detachably retaining in such position, a scratch-pad or piece usually of the character such as is used with safety or Swedish matches.

The present invention has for its principal objects to provide a novel and simply-constructed match-box or case for the reception of safety or Swedish matches, and also to provide in connection with the hinged members of the match-box or case, a novel and simply constructed, as well as an easily manipulated, scratch-pad or piece-retaining means, for properly retaining the scratch-pad or piece in its operative position upon the inner face of one of the said hinged members, and also permitting the quick and easy removal of the scratch-pad or piece when the same has been rendered useless, to replace the same with a new scratch-pad or piece.

The invention has for its further object to provide a match-box or safe for the reception of safety or Swedish matches in which the scratch-pad or piece-retaining means is of such construction, that the side-members of the usual cardboard or thin wooden boxes in which the matches are dispensed to the public can be broken away and readily placed and secured in position within the match-box or case, for the purpose of igniting the matches thereon, and to be easily replaced by similar scratch-pieces, when the former scratch-piece or pieces have been

rendered useless by the constant scratching of the matches thereon.

Other objects of the present invention not at this time more particularly enumerated will be clearly understood from the following detailed description of the present invention.

With the various objects of the present invention in view, the said invention consists, primarily, in the novel match-box or case hereinafter set forth; and, the invention consists, furthermore, in the novel means for detachably securing within the match-box or case a scratch-pad or piece for the ignition thereon of safety or Swedish matches, as well as in the general arrangements and combinations of the several devices and parts, and the details of construction of the same, all of which will be more fully embodied in the clauses of the claim which are appended to and which form an essential part of the said specification.

The invention is clearly illustrated in the accompanying drawings, in which:—

Figure 1 is a plan view of a match-box or safe embodying the principles of the present invention, the hinged members of the match-box being represented in their opened relation, so as to show more particularly the means for detachably securing the scratch-pad or piece upon the inner surface of the lid or cover of the match-box.

Fig. 2 is a longitudinal vertical section of the match-box or case, said section being taken on line 2—2 in said Fig. 1; and Fig. 3 is a transverse vertical section of the cover-member, said section being taken on line 3—3 in said Fig. 1, looking in the direction of the arrow x.

Fig. 4 is a detail vertical section, taken on line 4—4 in said Fig. 1; and Fig. 5 is a similar section taken on line 5—5 in said Fig. 1, both of said views being made on an enlarged scale.

Similar characters of reference are employed in the said above described views, to indicate corresponding parts.

Referring now to the said drawings, the reference-character 1 indicates a match-box or other suitable case, comprising a pair of hinged members 2 and 3, the member 2 being surrounded by marginal flangelike portions 4, and the member 3 being likewise surrounded by marginal flange-like portions 5,

so as to provide a pair of shell-like members, one of which, as 2, provides the main body, and the other member 3 providing the cover or lid of the box or case.

- 5 At their proper marginal flange-like portions of the said body and cover, respectively, the portion 4 is formed with pintle-receiving ears 6, and the portion 5 is also formed with corresponding pintle-receiving ears 7, all being arranged in a manner to receive a pintle 8, and whereby the body 2 and lid or cover 3 are hinged together, so as to be closed one upon the other. At its front edge, the flange-like portion of the body 2 is 15 provided with a suitably disposed and suitably constructed spring-catch, as 9, formed with a finger piece 10 and a catch-piece or latch-nosing, as 11, adapted to be sprung into holding and locking engagement with 20 an inwardly extending ledge or projection 12 with which the marginal portion 5 at the front of the lid or cover is provided, as will be clearly evident from an inspection of Figs. 1 and 2 of the drawings.
- 25 Suitably disposed over the rear portion of the said body 2 is a plate 13, formed with downwardly extending side-flanges 14 and a downwardly extending rear flange 15, said flange 15 being formed with a tongue-like member or extension, as 16, which is bent rearwardly and then forwardly and upwardly, in the manner shown more particularly in Fig. 2 of the drawings, so as to provide a loop or eye, as 17, which is suitably mounted upon a portion of the previously mentioned pivot-pin or pintle 8. At their forward edge-portions 18, the said side-flanges 14 are cut away, as at 19, thereby providing edge-portions 20 with which suitably formed retaining tongues or lugs, as 21, and which extend inwardly from the opposite side-flanges 4 of the body 2 are adapted to be brought into holding engagement, so as to permanently secure said plate 13 in position and with the member 2 to provide a suitable match-receiving pocket or chamber 22.
- 23 The means for retaining a piece or pieces 50 23 in detachable relation upon the inner surface of the lid or cover 3, said piece or pieces 23 being prepared with the usual scratching surface for the ignition of safety or Swedish matches, consists of a clamping or retaining plate 24, which is suitably bent or curved 55 along one of its marginal edge-portions, as at 25, for the proper slipping of the end-portion of the piece or pieces 23 beneath said plate 24 when the latter has been secured in position. At its marginal edge, opposite the 60 curved edge 25, the said plate 24 is provided with a series of pintle-receiving ears or lugs 26, and the intervening spaces 27, the said ears or lugs 26 having permanently mounted therein a pair of pivot-pins or pintles 28 and 65 29, extending from the opposite end-ports

tions of the plate 24, said pins extending across the said intervening spaces 27, but being of such lengths that the centrally disposed intervening space 27 is left clear, as shown in Figs. 1 and 3 of the drawings, to 70 receive the catch-piece or latching-nosing 11, when the lid or cover 3 is closed down upon the body 2, as will be evident. Extending downwardly from the said previously-mentioned ledge or projection 12 of the marginal 75 flange-like portion 5 of the lid or cover 3 are suitably formed tongue-like members, as 30, providing suitable loops or eyes 31, as will be seen from an inspection of Figs. 1, 3 and 4 of the drawings, said loops or eyes 31 being 80 properly disposed and arranged in the corresponding spaces 27, and serving as a means for pivotally mounting the said clamping or retaining plate 24 upon the respective pins or pintles 28 and 29, as shown.

To cause the curved edge-portion 25 of the said clamping or retaining plate 24 at all times to positively bear upon the inserted end of the piece or pieces 23, a coiled spring, as 32, is mounted upon a portion of one of 90 said pins, as 28, extending across the corresponding space 27, said spring having one of its end-portions 33 bearing upon the plate 24, and having its other end-portion 34 extending upwardly into bearing contact with 95 a slotted portion, as 35, with which the said ledge or projection 12 may be provided, as illustrated in Figs. 1 and 5 of the drawings.

The result of this arrangement of the spring 32 and its end-members is that the 100 said clamping or retaining plate is always held in its operative position, and permits of the scratch-pad or piece 23 to be easily slipped into its operative position, or to be removed from beneath said plate 24, as the 105 case may be, without any necessity of having to lift or raise said plate manually.

Any further detailed description as to the construction of the device and as to its operation is deemed unnecessary, except to say 110 that the match-box or case thus made is neat and compact in its construction, and very useful.

Of course, I am aware that changes may be made in the general arrangements and 115 combinations of the several devices and parts, as well as in the details of the construction of the said parts, without departing from the scope of the invention as set forth in the foregoing specification and as 120 defined in the clauses of the claim which are appended thereto. Hence, I do not limit my present invention to the exact arrangements and combinations of the several devices and parts as described in the said specification, nor do I confine myself to the exact 125 details of the construction of the said parts, as illustrated in the accompanying drawings.

I claim:

1. In a match-box or case comprising a 130

- body-member and a hinged cover-member, a clamp-plate pivotally connected within said cover-member at one end thereof so as to extend laterally across said end, said clamp-plate occupying but a small portion of the longitudinal extent of said cover-member, spring-means for depressing the free end of said clamp-plate toward the inner surface of said cover-member, and as thus disposed 5 adapting the same to engage a small portion of the end of a match-striker piece to grip and thus retain the same against the inside of said cover-member with the major portion of its surface unobstructed and exposed 10 for use, and the free marginal edge of said clamp-plate being turned outwardly to afford means to engage said clamp-plate to raise the same for the insertion or removal of a match-striker piece. 15 2. A match-box or case comprising a body-member and a cover-member hinged thereto, said body-member being adapted to receive matches, marginal flange-like portions connected with said members, a spring-catch 20 connected with said body-member, an inwardly extending ledge connected with the outer end of said cover-member with which said spring-catch can be forced into retaining engagement, a clamping plate within 25 said cover-member, said plate being provided with pintle-receiving ears, pintles mounted in said ears, tongue-like members connected with said ledge, said tongue-like members extending around and beneath said 30 35 pintles for pivotally mounting said clamping plate within said cover-member, and said clamping-plate having a centrally located cut-out portion at its hinged edge through which said spring-catch passes to holding 40 engagement with said ledge. 3. A match-box or case comprising a body-member and a cover-member, marginal flange-like portions connected with said
- members, pintle-receiving ears also connected with said members, a pintle mounted in 45 said ears for pivotally connecting said members, a plate within said body-member, said plate having downwardly extending side-flanges and a downwardly extending rear-flange, a tongue-like extension extending 50 rearwardly from said rear-flange and then forwardly and upwardly around the said pintle, and fastening means connected with said body member and secured to the side-flanges of said plate, thus providing an inclosed compartment at one end of said body-member. 55
4. A match-box or case comprising a body-member and a cover-member, marginal flange-like portions connected with said members, a pintle mounted in said ears for pivotally connecting said members, a plate within said body-member, said plate having downwardly extending side-flanges and a 60 downwardly extending rear-flange, a tongue-like extension extending rearwardly from said rear-flange and then forwardly and upwardly around the said pintle, the said side-flanges being provided with cut-away portions, and retaining lugs extending inwardly from the side-flanges of said body-member, said retaining lugs extending into the cut-away portions of the side-flanges of said plate, and being in holding engagement with 65 the said side-flanges of said plate, thus providing an inclosed compartment at one end of said body-member. 70
- In testimony, that I claim the invention set forth above I have hereunto set my hand 80 this 23rd day of February, 1917.

BENNO vom EIGEN.
